SCREW CAP AND PACKAGE

Louis A. Von Till, Brooklyn, N. Y., assignor to
 Anchor Cap & Closure Corporation, Long
 Island City, N. Y., a corporation of New York

Application January 10, 1933, Serial No. 650,949

14 Claims. (Cl. 215—44)

The present invention relates to screw caps and sealed packages, and more particularly to lug screw caps and packages provided therewith. Lug screw caps are easier to apply and remove than continuous thread caps. One or more turns are required to apply or remove continuous thread caps, while a friction of a turn will apply or remove lug caps. In addition, the threads on a continuous thread cap tend to grip both the upper and lower sides of the container thread and sometimes "freeze" on the thread of the caps, while a fraction of a turn will apply or remove. Lug caps, as a class, also form more secure seals because continuous thread caps seldom grip the rim of the container throughout its circumference and the cap tends to cock up on one side forming improperly sealed packages.

One serious difficulty with lug caps is the accuracy required in the manufacture thereof, and the corresponding accuracy required in the manufacture of the glass containers to which they are applied. Because of the low price at which the large quantities of caps and containers are sold, it is not possible to gauge and inspect individual caps and containers for correctness in size, hence it is not possible to properly reject the oversize and undersize containers. Definite tolerances have been worked out for the various glass companies and these companies endeavor to keep the variations in the glass within the limits prescribed, but frequently fail to do so. Where the thread of the glass is too low on the container, the lug tends to ride over the thread, which raises one side of the cap and impairs the seal. Where the thread is too high on the container, one side of the cap is pulled down with insufficient force to form a tight seal. In either case, the seal is defective and the packages are likely to spoil. Where the caps fail to work properly, the packer calls in both the cap company and the glass companies to find out the trouble, and dispute arises as to where the fault lies. For a number of years, there has been a persistent demand for a lug cap which will accommodate a greater range of size variations in glass containers.

The present invention aims to limit or minimize the above difficulties and to provide a lug cap which has greater flexibility, and which is capable of forming a perfect seal on both oversized and undersized containers, and aims to do this without increasing the cost of the cap.

An object of the invention is to provide an inexpensive lug cap adapted to accommodate a greater range of size variations in glass containers.

Another object of the invention is to improve the seal formed by lug closures.

Another object of the invention is to increase the resiliency and flexibility of the closure.

Another object of the invention is to facilitate application and removal of caps by providing greater clearance between the skirt of the cap and the container threads.

Another object of the invention is to provide corrugations shaped to enhance the appearance of the cap.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein

Fig. 1 is a sealed package illustrating a preferred embodiment of the invention;

Fig. 2 is a fragmentary enlarged sectional view, through one of the lugs of the cap, illustrating details of the construction;

Fig. 3 is an enlarged sectional view corresponding to Fig. 2, taken intermediate the lugs of the cap;

Fig. 4 is an enlarged fragmentary sectional view illustrating the cap applied to a container;

Fig. 5 is an enlarged fragmentary sectional view illustrating another embodiment of the invention;

Fig. 6 is an enlarged fragmentary sectional view illustrating still another embodiment of the invention; and

Fig. 7 is an enlarged fragmentary sectional view illustrating a further modification of the present invention.

Referring again to the drawing, there is shown a container 1 having thread projections 2 at the upper end thereof spaced above a shoulder 4. A closure cap 5 is applied to the container and may have a cover portion 6 and a depending skirt 7, with the lower edge of the skirt rolled outwardly into a bead or wire edge 8. Suitable lugs 9 may be formed from the beaded edge by pressing portions thereof inwardly at intervals about the periphery thereof to engage with the thread projections 2 on the container. A suitable liner 10 of cardboard or the like may be provided in the upper part of the cap for forming a seal on the

rim of the container. The cap may be applied to the container with a fraction of a turn, and removed in like manner.

The present closure differs from present lug caps in that the cover portion of the cap is extended outwardly a very substantial distance beyond the rim of the container, as shown at 11, and the skirt of the cap is tapered inwardly toward the bottom thereof so that the upper inner 10 diameter of the skirt 12 is substantially larger than the inner diameter at the lower portion 13 of the skirt. These and other differences in the construction of the cap produce certain very desirable results. The construction of the bottom 15 of the skirt permits a snug fit of the lugs 9 under the thread projections 2 of the container. The additional space provided by the upper flare of the skirt of the cap above the lugs affords ample clearance between the skirt of the cap and the 20 thread projections 2 on the container. Hence, when the cap is applied or removed from the container, the only friction to be overcome is that between the lugs of the cap and the threads on the container. With the closure manufactured 25 at the present time, oversized containers may engage the inner side of the skirt of the cap, making the cap more difficult to turn, either on application or removal. In addition, the containers are made in split molds and, hence, there are two 30 mold marks or small fins extending outwardly from the side of the glass container. These small fins are engaged by the corrugations on present types of closures and small particles of glass are broken from the container and may get into the 35 product, in addition to scratching up the inner side of the cap.

Where a lug cap is applied to a container with too much force, or to a container having a thread slightly lower than it should be, there is 40 a tendency for the lug to ride up over the thread on the container and raise or bulge a portion of the cover portion of the cap, forming a defective seal. With the constricted skirt, as illustrated herein, any tendency for the lug to ride over the 45 thread of the container is minimized by reason of the substantial overhang of the cover portion of the cap, giving greater flexibility, as shown more particularly at 15. In other words, the cover portion of the cap, overhanging the side of the 50 container is essentially like a cantilever, and the longer the cantilever, the more it can be bent downwardly to take up greater variations in the position of the thread on the container. This is shown more particularly in Fig. 4. Any tendency 55 of the lugs to ride over the thread expands the bottom of the skirt, and since the skirt is not vertical, but at an acute angle, outward expansion of the skirt brings it nearer to vertical and increases the distance between the lug and the cover portion of the cap. This is shown more particularly by the dotted line 16, in Fig. 2, which is an arc formed by swinging the lower side of the lug about the junction of the skirt and the cover portion of the cap.

60 To increase further the effectiveness of the seal and the flexibility of the cap, there is provided an annular depression or groove 17 directly above the rim of the container. This depression concentrates the sealing pressure over a small area and increases its effectiveness. In addition, it increases the cantilever effect and the flexibility of the overhang, which the cover portion has beyond the side wall of the container.

65 It is to be understood that the groove 17 may be omitted if desired and, likewise, the center of

the cover portion of the cap may be domed or otherwise shaped to suit the individual taste. Corrugations 18 are preferably formed in the skirt of the cap and extend substantially from the top to the upper side of the wire edge. While corrugations of any suitable shape may be utilized, preferably, the corrugations increase in depth from the upper part to the lower part thereof, and are pressed outwardly from the skirt of the cap. By forming the corrugations in this manner, the inwardly tapered skirt appears to be more nearly cylindrical and the wire edge of the cap projects a lesser distance from the bottom of the skirt. The wire edge on the ordinary cap is commonly thought to be cumbersome in appearance and considerable effort has been made to reduce its size in an effort to improve the appearance of the cap. The present inwardly tapered skirt decreases the difference between the external diameter of the wire edge and the external diameter of the top of the cap, thereby improving the appearance of the cap, which is also accentuated by the shape of the corrugations.

In the construction illustrated in Fig. 5, the sealing zone is inclined with respect to the plane of the cover portion, as shown at 20. Preferably, the inner side of the inclined sealing zone is substantially at the inner side of the rim of the container. By having the sealing zone inclined as shown, the liner is spaced from the inclined portion and forced upwardly against it during the sealing operation. This facilitates the accommodation of irregularities and improves the seal by making the sealing operation continue for a greater period.

In Fig. 6, a slightly different construction is shown wherein the upper portion 25 of the cap skirt is substantially cylindrical and may be provided with suitable corrugations 26. Below the cylindrical zone, an annular inwardly inclined portion 27 is provided, having a wire edge 8 with thread engaging lugs 9 formed therein. By reason of the inclined zone 27, the skirt of the cap is substantially resilient and the upright zone 25 extends away from and out of contact with the threads of the container, whereby a better seal may be provided.

In Fig. 7 the skirt of the cap is flared outwardly at 29 and flared inwardly at the lower portion 30 thereof, as shown at 30. Preferably, an intermediate, substantially cylindrical zone 31 may be provided, wherein suitable corrugations are formed to facilitate gripping the cap. The flared zones 29 and 30 absorb excessive sealing forces effective upon the skirt of the cap, whereby a better fit between the cap and container is provided, even if they vary from a prescribed standard. In addition, the cap skirt is out of contact with the container threads and binding engagement is prevented. If a cap is sealed too tightly, the skirt may be tapped or pressed inwardly to increase the length thereof, whereby the lugs are moved slightly out of contact with the container threads and removal of the cap is facilitated.

In operation, the closure cap is applied to the container in the usual manner. The lugs 9 slip between the ends of the projections 2, and a quarter turn applies the cap, as shown more particularly in Figs. 1 and 4. As the cap is screwed home, the pressure on the lugs is considerable. Irregularities in the glass are taken up by the increased flexibility of the cap occasioned by the increased amount of overhang which the cover portion of the cap has with respect to the con-

tainer, and by the increased distance between the cover portion and the lug occasioned by outward pressure on the skirt of the cap, which, as pointed out hereinbefore, tends to press the skirt outwardly to its vertical position, thereby increasing the distance between the cover portion and the lug. The reduction in the size of the lower part of the cap causes the lugs to fit snugly over the projections 2, with ample clearance between the skirt of the cap and the outer sides of the projections. In other words, the cap is snug where it should be snug, and has ample clearance where clearance is needed.

It will be seen that the present invention provides a lug closure cap having greater flexibility than caps known heretofore. The closures will accommodate a greater range of variations in the size of the containers, without endangering the seal in any way. The closures may be applied or removed with greater ease because of this flexibility, and because of ample clearance between the skirt of the cap and the threads on the container. The inward taper of the skirt and the reduced diameter of the bottom thereof causes a very snug fit of the lugs of the cap beneath the threads of the container and minimizes the tendency of the lugs to ride over the threads. In addition, any outward movement of a lug in an effort to ride over the thread causes the lug to move downwardly, whereas if the skirt were cylindrical, the lug would move upwardly under similar circumstances. The downward movement of the lug will, of course, tend to compensate for the irregularity of the position of the thread on the container. The closure is simple in construction and can be made with the same machinery and at substantially the same cost as present closures.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. As an article of manufacture, a closure cap comprising the combination of a cover portion, a depending skirt, said skirt being constricted inwardly from the upper part to substantially the lower part thereof, and lugs formed on the bottom of said skirt.

2. As an article of manufacture, a closure cap comprising the combination of a cover portion, a depending skirt, said skirt being inclined inwardly from the upper to the lower part thereof whereby the lower part of said skirt has a smaller diameter than the upper part thereof, a rolled edge at the bottom of said skirt, and lugs formed from said lower edge for engagement with threads on a container.

3. As an article of manufacture, a closure cap comprising the combination of a cover portion, a depending skirt, said skirt being tapered inwardly to reduce the diameter of the lower part thereof, a rolled edge at the bottom of said skirt, and lugs formed by pressing inwardly portions of said rolled edge, the increased size of the upper part of the skirt being adapted to afford ample space for the threads on the container, without engaging the outer sides thereof.

4. As an article of manufacture, a closure cap comprising the combination of a cover portion, a depending skirt, said skirt being tapered inwardly from the top to the bottom thereof to afford ample clearance for the threads of the con-

tainer, a rolled edge at the bottom of said skirt, and lugs formed from said rolled edge by pressing inwardly portions thereof, and corrugations in said skirt.

5. As an article of manufacture, a closure cap comprising the combination of a cover portion, a depending skirt, said skirt being tapered inwardly toward the bottom thereof to afford clearance for the threads of the container, and lugs formed by pressing inwardly portions of the bottom of the skirt, and vertical corrugations in the skirt of the cap, said corrugations being pressed outwardly therefrom and extending outwardly further at the lower portion of the skirt than at the upper portion thereof. 15

6. As an article of manufacture, a closure comprising a cover portion, a depending skirt, a rolled edge at the bottom of said skirt and lugs formed by pressing inwardly portions of said rolled edge, the bottom of said skirt being substantially smaller than the upper portion thereof to afford greater flexibility when the cap is applied to a container. 20

7. As an article of manufacture, a closure cap comprising the combination of a cover portion, a depending skirt, a rolled edge at the bottom of said skirt and lugs formed from said rolled edge, said skirt being tapered inwardly from the upper portion thereof to the lower portion thereof, and corrugations in said skirt increasing in depth 30 from the upper part thereof to the lower part thereof.

8. As an article of manufacture, a closure cap comprising the combination of a cover portion, a depending skirt having an annular inwardly inclined portion at the lower part thereof, and lugs formed on the bottom of said skirt. 35

9. As an article of manufacture, a closure cap comprising the combination of a cover portion, a depending skirt having a cylindrical zone provided with corrugations and an inwardly inclined zone below said cylindrical zone, and container engaging means formed on the bottom of the skirt. 40

10. A sealed package comprising the combination of a container having projections thereon, a closure cap having a cover portion and depending skirt, the internal diameter of said skirt being smallest at the bottom thereof to increase the extension of the cover part of the cap beyond the rim of the container, a rolled edge on the bottom of said skirt, lugs formed from said rolled edge adapted to engage the projections on the container and a sealing member intermediate the rim of the container and the cover of the cap. 45 50

11. A sealed package comprising a container having thread projections at the upper end thereof, a screw closure cap having a cover portion and a depending skirt, said skirt being tapered inwardly to increase the distance which the cover portion of the cap extends outwardly over the rim of the container to allow a greater range of variations from a prescribed standard in said thread projection, a rolled edge formed at the lower edge of said skirt, projections formed from 65 said rolled edge to engage the projections on the container and a sealing member intermediate the rim of the container and the cover of the cap.

12. As an article of manufacture, a screw closure cap comprising the combination of a cover portion, a depending skirt having an annular inwardly inclined portion at the lower part thereof, a rolled edge at the bottom of said skirt and inwardly extending container engaging lugs formed from said rolled edge. 70 75

13. As an article of manufacture, a screw closure cap comprising the combination of a cover portion, a depending skirt having a substantially cylindrical zone provided with corrugations, an inwardly extending zone below said substantially cylindrical zone, an outwardly rolled edge at the bottom of the skirt below said inwardly extending zone, and container engaging means formed from said rolled edge.
- 5 14. As an article of manufacture, a screw closure cap comprising the combination of a cover

portion, a depending skirt having a substantially cylindrical zone provided with corrugations, an inwardly extending zone below said substantially cylindrical zone, an outwardly rolled edge at the bottom of the skirt below said inwardly extending zone, whereby said rolled edge does not extend outwardly substantially beyond the cylindrical zone, inwardly extending container engaging lugs formed from said rolled edge and a sealing member in said cap.
